COMPOSITIONS SUITABLE FOR USE AS GAS
AND POWER PRODUCING LIQUIDS

John Whetstone, West Kilbride, and James Taylor, Saltcoats, Scotland, assignors to Imperial Chemical Industries Limited, a corporation of Great Britain

No Drawing. Application July 17, 1946, Serial No. 684,242. In Great Britain August 24, 1945

1 Claim. (Cl. 52—14)

1 The present invention is concerned with the provision of substantially anhydrous homogeneous compositions suitable for use as gas- and power-producing liquids for use in explosive compositions or otherwise for instance in internal combustion engines or in reaction propelled or jet propelled devices.

It is an object of the invention to provide chemically stable non-volatile power producing compositions that are liquid at or about ordinary atmospheric temperatures.

It is known that ammonium nitrate can react with liquid ammonia to form Diver's liquid, but this liquid is unstable and has a considerable vapour pressure of ammonia.

Ammonium nitrate is the most important energy and gas-producing salt used in the explosives industry, and can also be employed in conjunction with oxidisable materials for the production of power in other ways than by explosion, but to a certain extent the crystalline form of this compound limits its application. For instance the amount of ammonium nitrate that can be included in nitroglycerine gelatine explosive compositions is limited rather by the necessity of maintaining the proper compactness of the explosive than by the considerations of sensitivity. Again, fuels for internal combustion engines must be liquids capable of flow at ordinary or only slightly raised temperatures. To dissolve the ammonium nitrate in water would seriously detract from the power producing value of the composition. A chemically stable substantially anhydrous homogeneous composition containing the ammonium nitrate and a material oxidisable by it in solution at or about room temperatures would thus be of considerable value as a power producing liquid, but so far as we are aware such liquid has never been produced.

It is known that ammonium nitrate and urea form a binary eutectic having a melting point of 44.7° and containing 47% urea (Howells, Journ. Chem. Soc. 1929, p. 910), and that a ternary eutectic can be formed containing 45% urea, 47.5% ammonium nitrate and 7.5% sodium nitrate and having a melting point of 37.1° (Howells, Journ. Chem. Soc. 1930, p. 2010). It is also known that a ternary eutectic having a melting point of 42.5° can be produced from 45.5% urea, 52.0% ammonium nitrate and 2.5% resorcinol (Hrynakowski Z. Krist. 94, p. 358 (1938)).

We have now found that by the inclusion of one or more compounds of the kind hereinafter defined in mixtures containing ammonium nitrate and urea it is possible to provide substantially an-

hydrous chemically stable non-volatile eutectic and non-eutectic compositions that are liquid at temperatures not substantially higher than room temperature.

5 The one or more compounds which are to be included in the ammonium nitrate-urea compositions are ammonium nitrate fusion point depressing inorganic salts and organic materials which are of low molecular weight and are freely soluble in fused ammonium nitrate and urea; are not highly associated in ammonium nitrate solution (such substances are usually found to be freely water soluble in the cold); do not form insoluble or sparsely soluble salts by decomposition with ammonium nitrate, or by co-ordination with urea, to an extent that the desired reduction in the fusion point of the ammonium nitrate urea eutectic or composition is not attained.

10 The following are examples of suitable compounds which can be added preferably two or more than two at a time to ammonium nitrate and urea mixtures namely ammonium sulphamate, ammonium thiosulphate, ammonium formate, ammonium acetate, ammonium thiocyanate, ammonium hypophosphite, acetamide, propionamide, anhydrous sodium acetate, methylamine nitrate.

15 The following inorganic salts are described by Beilstein as giving addition compounds with urea and are thus unsuitable as additions at least in any quantity: sodium chloride, ammonium chloride, calcium chloride, zinc chloride, cadmium chloride, mercuric chloride, calcium bromide, magnesium bromide, calcium iodide, sodium nitrate, silver nitrate, calcium nitrate, magnesium nitrate.

20 The following substances which are freely water soluble and of low molecular weight have been found to raise the crystallising temperature of the ammonium nitrate-urea eutectic; sodium perchlorate, ammonium fluoride, urea nitrate, potassium dihydrogen phosphate. These substances are thus unsuitable as additions.

25 According to the present invention therefore substantially anhydrous homogeneous compositions suitable for use as gas and power producing liquids of ammonium nitrate and urea include such quantities of one or more of the compounds of the kind hereinbefore defined that the said compositions are liquid at atmospheric temperature ranges.

30 Although the ratio of the ammonium nitrate to urea in the binary eutectic formed by these two substances is 53:47 the ratio generally preferred is 50 to 30 or 50 to 25 in order to keep

the oxygen value of the mixtures nearer "balance." This necessitates the choice of the one or more of the compounds hereinbefore defined to be such that they will dissolve the excess ammonium nitrate.

It has been found that mixtures of the ammonium nitrate-urea eutectic plus about a total of 20-25% of two or more of the compounds hereinbefore defined have eutectics fusing in the range -10° C. to +30° C.

As it is usually desirable as hereinbefore mentioned, that for use in explosives the oxygen values of the said anhydrous homogeneous admixtures should not be allowed to become unfavourably negative, the ammonium nitrate content is usually arbitrarily kept in the region of 45-55% and consequently such liquid mixtures are not true eutectic compositions, though their low fusion points are due to the formation of eutectics.

The following are examples of substantially anhydrous homogeneous admixtures according to the invention wherein the parts are parts by weight.

Example 1

	Parts
Ammonium nitrate	50
Urea	33
Methylamine nitrate	17

The urea and methylamine nitrate together give a liquid containing suspended matter at 20° C. The ammonium nitrate is dissolved in portions and gives a product almost completely liquid at 20° C.

Example 2

	Parts
Ammonium nitrate	50
Urea	25
Methylamine nitrate	17
Ammonium sulphamate	8

The urea, methylamine nitrate and ammonium sulphamate become liquid when mixed together at room temperature. The ammonium nitrate dissolves almost completely on addition. There is little change in the amount of suspended solid between 18° and 55° C. The oxygen value per gram is -0.18.

Example 3

	Parts
Ammonium nitrate	50
Urea	25
Ammonium formate	15
Ammonium sulphamate	10

On mixing the above four ingredients together at a somewhat raised temperature a slightly viscous liquid is obtained. On cooling crystallisation sets in at 17° C. and the temperature rises to 23° C. and the liquid becomes pasty.

The oxygen value per gram is -0.22.

Example 4

	Parts
Ammonium nitrate	50
Urea	25
Ammonium formate	15
Ammonium hypophosphite	10

The above four ingredients are mixed and fused together at a somewhat raised temperature. A little crystallisation occurs on cooling to 21° C. but the melt is mostly liquid at room temperature.

The oxygen value is -0.25.

Example 5

	A	B	C
Parts	Parts	Parts	Parts
Ammonium nitrate	45	40	50
Urea	30	30	25
Ammonium formate	10	15	10
Ammonium acetate	15	15	15
Oxygen value per gram	-0.38	-0.43	-0.33

The mixture A is completely liquid at 20° C. though cooling below 14° C. induces the separation of long-needle-like crystals, probably ammonium nitrate.

Mixture B, containing less ammonium nitrate, is fluid at -10° C.

Mixture C is partly liquid at room temperatures. The differences in properties according to variations in the ratio of four components are also shown by the following table:

Example 6

	A	B	C
Parts	Parts	Parts	Parts
Ammonium nitrate	50	45	40
Urea	25	30	30
Ammonium formate	15	15	15
Acetamide	10	10	15
Oxygen value per gram	-0.34	-0.39	-0.48

Composition A, on cooling, first crystallises at 28° C. and is still very fluid at 20° C. The liquid when cooled to 0° C. remains supercooled but on stirring complete solidification ensues with rise of temperature to 15° C.

Composition B is liquid at room temperatures and crystallises partly at 15° C.

Composition C does not crystallise after 48 hours at -10° C.

Example 7

	A	B
Parts	Parts	Parts
Ammonium nitrate	50	40
Urea	25	30
Ammonium acetate	15	15
Acetamide	10	15
Oxygen value per gram	-0.42	-0.55

These two mixtures illustrate once again that the ratio of the four components is of great importance, for whereas mixture A becomes pasty with suspension of crystals at 30° C. mixture B withstands a few hours storage at -10° C. without crystallisation. This is due to supercooling. On prolonged standing at -10° C. the liquid becomes filled with crystals which do not wholly redissolve at room temperatures.

Example 8

	Parts
Ammonium nitrate	45
Urea	30
Acetamide	10
Ammonium acetate	5
Ammonium formate	10

On mixing the above five ingredients at a somewhat raised temperature a slightly viscous liquid is obtained. On cooling crystallisation sets in at 15° to 20° C.

We claim:

A gas and power producing composition comprising a blend of from 40 to 55 parts by weight

of ammonium nitrate, from 25 to 30 parts by weight of urea, and from 20 to 25 parts by weight of ammonium nitrate freezing point depressants selected from the group consisting of ammonium sulphamate, ammonium thiosulphate, ammonium formate, ammonium acetate, ammonium thiocyanate, ammonium hypophosphite, acetamide, propionamide, and methylamine nitrate, said blend having a fusion point in the range of -10° to $+30^{\circ}$ C.
